Primary Examiner — Maria J. Edwards

(57) **CLAIM**

The ornamental design for a fingernail-accommodating glove, as shown and described.

DESCRIPTION

FIG. 1 is a top front perspective view of a first embodiment of a fingernail-accommodating glove showing my new design;

FIG. 2 is a bottom rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof;

FIG. 8 is a left elevational view thereof;

FIG. 9 is a top front perspective view of a second embodiment of a fingernail-accommodating glove showing my new design;

FIG. 10 is a bottom rear perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a right elevational view thereof;

FIG. 16 is a left elevational view thereof;

FIG. 17 is a top front perspective view of a third embodiment of a fingernail-accommodating glove showing my new design;

FIG. 18 is a bottom rear perspective view thereof;

FIG. 19 is a front elevational view thereof;

FIG. 20 is a rear elevational view thereof;

FIG. 21 is a top plan view thereof;

FIG. 22 is a bottom plan view thereof;

FIG. 23 is a right elevational view thereof; and,

FIG. 24 is a left elevational view thereof.

The broken lines showing a glove body in FIGS. 1-24 are included for the purpose of illustrating environmental structure and form no part of the claimed design.
